UNITED STATES PATENT OFFICE.

GEORGE A. MEAGHER, OF MONTREAL, QUEBEC, CANADA.

DESIGN FOR A SKATE.

43,766.

Specification for Design.

Patented Apr. 1, 1913.

Application filed September 5, 1911. Serial No. 647,779. Term of patent 3½ years.

To all whom it may concern:

Be it known that I, GEORGE A. MEAGHER, a subject of the King of Great Britain, residing at the city of Montreal, Province of Quebec, and Dominion of Canada, have invented a new, original, and ornamental Design for Skates, of which the following is a specification, reference being had to the accompanying drawings, forming a part thereof.

Figures 1 and 2 represent respectively a side elevation and plan view of a skate showing my invention.

I claim:

The ornamental design for a skate, as shown.

GEORGE A. MEAGHER.
